UNITED STATES PATENT OFFICE

131,725

DESIGN FOR A VULCANIZER

Charles E. Bowes, Indianapolis, Ind., assignor to
Bowes Seal Fast Corporation, Indianapolis,
Ind., a corporation of Indiana

Application November 6, 1941, Serial No. 104,068

Term of patent 14 years

To all whom it may concern:

Be it known that Charles E. Bowes, a citizen of the United States, residing at Indianapolis, in the county of Marion and State of Indiana, has invented a new, original, and ornamental Design for a Vulcanizer, of which the following is a specification, reference being had to the accompanying drawings, forming a part thereof.

This application is a continuation-in-part of my application, Serial No. D-94,490, filed in the United States Patent Office August 19, 1940, now abandoned.

In the drawings:

Fig. 1 is a side elevational view of a vulcanizer embodying my new design;

Fig. 2 is a top plan view thereof;

Fig. 3 is a front elevational view thereof; and

Fig. 4 is a rear elevational view.

I claim:

The ornamental design for a vulcanizer, substantially as shown.

CHARLES E. BOWES.
